HERMAN YSSKIN, OF NEWARK, NEW JERSEY.

FOLDING TABLE.

1,189,645.

Specification of Letters Patent. Patented July 4, 1916.

Application filed June 1, 1914. Serial No. 842,041.

To all whom it may concern:

Be it known that I, HERMAN YSSKIN, a citizen of the United States, and a resident of Newark, county of Essex, and State of New Jersey, have invented certain new and useful Improvements in Folding Tables, of which the following is a specification.

This invention relates to a table that is adapted to be folded up or collapsed and thus be made available for transportation by a person, being particularly designed for tables such as are used by paper hangers, although it can be used for other purposes, the table being light and large enough, when set up, to provide the working space necessary. The invention is designed to provide a table of this kind which can be folded into a small space and it makes a long narrow bundle which can be easily taken on trolley cars and other public conveyances and takes up but little room, as it is adapted to be set vertically against a wall, the supporting legs of the table also being inclosed or included in the collapsed structure.

The invention consists primarily of a series of top sections which, when placed side by side, form the table top, but which can be nested when the table is knocked down, the nested sections receiving the folded supports or stands of the table, the whole being adapted to be strapped or otherwise bound so that the parts are held in place, as will be evident.

The invention relates further to details of construction which are illustrated in the drawing and described in the specification, these details being adapted to be changed in minor respects without departing from the scope of the invention as set forth in the claims.

The invention is illustrated in the accompanying drawing, in which—

Figure 1 is a top view of a table set up ready for use. Fig. 2 is a view of the back of the table shown in Fig. 1, and Fig. 3 is an end view of the table. Fig. 4 is an enlarged section on line 4 in Fig. 1. Fig. 5 is a section through the table when it is collapsed and the parts are nested and assembled. Fig. 6 is a perspective view of a preferred binding means for one end of the table, this view also showing a perspective view of one end of the table sections. Fig. 7 is a longitudinal section through one of the table sections. Fig. 8 is a detail view showing one form

of catch that can be used on the binding means to hold the parts of the table together, and Fig. 9 is a section showing a detail for supporting an edge section of the table when said edge section is thinner than the adjacent section.

The table is supported on suitable legs or stands 10, the type shown being of the kind that usually are used by paper hangers, consisting of legs 11 and legs 12 which are pivoted together at 13 and are arranged on each side of a bar 14 which can be raised to a horizontal position and is provided with notches 15 into which a staple 16 can be placed to hold the stand at various heights. So far as described this table is not new, and I do not wish to be limited to the exact type of stand shown.

Supported on the horizontal bar 14 is the table top which consists of table sections, these table sections being so constructed that they can be nested when the table top is collapsed, but being adapted to form a stiff top when they are extended and bound together to form the flat top of a table. In the form of table shown, which is a paper hanger's table, although the table can be used for other purposes, one of the table sections 17 is made of wood, this being preferred on account of the cutting that has to be done and the wood offers a better surface for cutting than the metal sections. It will be understood, however, that the end sections 17 can be made of metal or any other suitable material, if desired. The table sections 18 are preferably made of metal and are made U-shaped, that is, they are provided with side flanges, the whole having the appearance of a trough, these troughs then being turned bottom side up and arranged side by side so as to form a flat even top for the table, the flanges 19 of these tops abutting and holding the sections in alignment. To one of the end sections, and in the illustration I have selected the end section 17 as being the one, is secured a latch 20 which is pivoted as at 21 to the end section so that it can swing thereon, being adapted to swing against the side of the section 17 when the sections 18 are removed, but to be swung outward and receive the ends of the sections 18, since the latch 20 is provided with a channel 22, the top and bottom flanges 23 and 24 respectively receiving the ends of the sections 18 shown in

95

100

110

Fig. 4, the flanges 19 being provided at their ends with chamfered or inclined lower edges 25. When the latch is swung to the locking position shown in Fig. 1 it receives the 5 ends of the sections 18 and supports these ends so that the table is level and the sections are properly aligned. The channeled or U-shaped cross-sectional form of the sections 18 stiffens them so that they are not 10 apt to bend or curve to an excessive extent, and a stiff table top is the resultant structure. The edge section 17 is usually made thinner than the sections 18 and in a case of this kind the section 18 adjacent to the 15 edge section 17 has one of its flanges 19 bent outward to form a lip 26 along that edge of the section 18 and thus support the edge section 17. When the latch 20 is attached to this thin section 17 it will still receive the 20 end of the section 18 on account of the thinned or chamfered ends of such sections 18 shown in Fig. 4. The sections 18 are made so that they are slightly different widths so that they will fit together when 25 nested, as shown in Fig. 5. One of the sections, that is, the section that is to be innermost of the nested ones, is provided with brackets 27 on its under surface, these acting as stops, the purposes of which will be described hereinafter.

When the table is to be set up, the stands 10 are erected at the proper points and the section 17 is laid across the stands and then the sections 18 adjacent to it, these being 35 properly arranged side by side, and then the latches 20 are swung so as to bind the parts together and hold them in their assembled positions. The table is now ready for use and it is quickly set up, as will be evident. 40 If desired, the latches can be locked in place, one form of lock being shown in Fig. 8, this consisting of a swinging catch 28 which is attached by suitable pivotal connection 29 to the end of the latch 20. The catch 28 has 45 a handle 30 and it engages a suitable holding element 31. In the form shown this consists of a stud or headed rivet over which the catch 28 is sprung. It will be evident, however, that any other form of catch which 50 is suitable for the purpose can be used in this device.

When the table is to be assembled, the latches 20 are swung back to release the end table sections 17 from the other table sections, and these latches 20 are then folded 55 against the sides of the end sections 17 so as to make a long narrow element of it. Then the sections 18 are nested as shown in Fig. 5, one being placed within the other, 60 the innermost of the sections being the one illustrated in Fig. 7 that has the brackets 27 attached to its inner face or under surface. In the space between these brackets or stops 27 and the side flanges 19 are placed the 65 stands 10, these stands being shown folded

in Figs. 5 and 7, the reference numeral 32 being used to indicate them in their folded positions and showing their situation in the knock-down structure. The nested sections, the folded stands 10 and the end sections 17 70 are now assembled as shown in Fig. 5, and a suitable binding means 33 is then passed around the bundle and tightened so as to hold all the parts in their positions. The binding means shown in the drawing consists of a strap having a suitable buckle 34, although it will be evident that other binding means and other means of securing said binding means can be employed.

The table, when collapsed, forms a long 80 narrow bundle which can be easily transported in trolley cars and the like, since it occupies but little room. In the type of ordinary paper hanger's tables the sections would be four or five inches wide and be 85 between five and six feet long so that the whole bundle would not exceed these requirements very much, which is a marked contrast to the old type of table made of wide boards which were thick and were placed one on top 90 of the other, usually requiring a wagon for their transportation. The end section 17 is usually made of wood as above described, but the intermediate sections are made of tin or other sheet metal which is bent up 95 into the form shown, and while the sections are stiff and form a substantial table top when they are assembled, they are light in weight, and the whole table, when collapsed and assembled as shown in Fig. 5, does not 100 weigh very much.

The table when made according to this invention is stiff by reason of the flanges, and a light metal can be used which, when bent up into the channeled form, provides 10 the necessary stiffness for the table.

It will be understood that the device can be lightened by stamping holes or openings therein at the proper places in order to cut away the material.

Having thus described my invention, I claim:

1. In a table, a foldable support, a flat top portion formed of channeled sections which are adapted to be nested, means for holding the sections side by side with their tops in the same plane, the sections when nested receiving the folded support, and means for holding the sections together when they are nested.

2. In a table, a pair of foldable stands, a top portion formed of long narrow channeled sections which are adapted to be laid side by side or nested, and a latch secured to one of the sections and adapted to hold the 12 sections side by side, one of said sections acting as a holder for the stands when folded.

3. In a table, a top portion formed of sections with longitudinal channels to provide 13

- for their being nested, and latches to engage the ends of the sections to hold them when they are side by side.
4. In a table, a top portion formed of sections with longitudinal channels to provide for their being nested, and latches to engage the ends of the sections to hold them when they are side by side, the latches being pivotally attached to selected sections.
- 10 5. In a table, a top portion formed of longitudinally arranged sections, the sections having flat tops and having side flanges depending from the longitudinal edges to form channels in the bottom of the sections whereby the sections are adapted to be nested, and latches swinging on one end section and engaging the ends of the remaining sections to hold them in position.
- 15 by the sections are adapted to be nested, and latches swinging on one end section and engaging the ends of the remaining sections to hold them in position.

6. In a table, a top portion formed of longitudinally arranged sections, the sections 20 having flat tops and having side flanges depending from the longitudinal edges to form channels in the bottom of the sections whereby the sections are adapted to be nested, latches swinging on one end section and 25 engaging the ends of the remaining sections to hold them in position, catches to lock the latches in holding position, and brackets arranged in the channel of at least one section.

In testimony that I claim the foregoing, I 30 have hereunto set my hand, this 28th day of May, 1914.

HERMAN YSSKIN.
